UNITED STATES PATENT OFFICE.

ELMER HARROLD, OF LEETONIA, OHIO, ASSIGNOR TO THE CRESCENT MACHINE COMPANY, OF LEETONIA, OHIO, A CORPORATION OF OHIO.

DESIGN FOR A GUARD FOR BAND-SAWS.

44,126.

Specification for Design.

Patented June 3, 1913.

Application filed January 3, 1913. Serial No. 740,036. Term of patent 7 years.

To all whom it may concern:

Be it known that I, ELMER HARROLD, a citizen of the United States, residing at Leetonia, in the county of Columbiana and State of Ohio, have invented a new, original, and ornamental Design for Guards for Band-Saws, of which the following is a specification, reference being had to the accompanying drawing, forming part thereof.

The figure is a perspective view of a guard embodying my design.

I claim:

The ornamental design for a guard for band saws as shown.

In testimony whereof, I have hereunto set my hand.

ELMER HARROLD.

Witnesses:

E. WARREN,
FREIDA CHELLIS.
